UNITED STATES PATENT OFFICE.

WILLIAM T. S. MARTIN, OF PHILADELPHIA, PENNSYLVANIA.

DESIGN FOR A LIGHT-PROJECTING GLASS PLATE OR PANEL.

SPECIFICATION forming part of Design No. 34,239, dated March 19, 1901.

Application filed August 28, 1899. Serial No. 728,795. Term of patent 14 years.

To all whom it may concern:

Be it known that I, WILLIAM T. S. MARTIN, a citizen of the United States, residing at Philadelphia, Pennsylvania, have invented a new and original Design for a Light-Projecting Glass Plate or Panel, of which the following is a specification.

My design is fully shown in the accompanying drawings, in which—

Figure 1 represents a view of one face of a light-projecting glass plate or panel embodying the design. Fig. 2 is a view of the opposite face of the same. Fig. 3 is a section on the line *a a*, Fig. 1; and Fig. 4 is a section on the line *b b*, Fig. 1.

On one face of my light-projecting glass plate or panel are convex projections or lenses 1 and lens-segments 1^a, disposed in longitudinal and transverse rows, so that the projections of one row will overlap those of the ad-

joining rows, the bases of the projections merging into the concave valleys 2, whereby said projections are separated from each other. On the opposite face of the light-projecting glass plate or panel are prism-bars 3. 25

The essential feature of the design comprises the prism-bar formation of one face of the glass plate or panel and the rows of convex projections with intervening concave valleys on the opposite face. 30

Having thus described my invention, I claim as new and desire to secure by Letters Patent—

The design for a light-projecting glass plate or panel, substantially as described and as shown in the accompanying drawings. 35

WILLIAM T. S. MARTIN.
